CLAIM

The ornamental design for a cruet as shown and described.

DESCRIPTION

FIG. 1 is a top isometric view of a cruet showing our new design.

FIG. 2 is a bottom isometric view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The dashed lines in the figures represent features of the cruet that form no part of the claimed design. The dash dot lines in FIG. 2 and FIG. 8 represent a boundary between claimed and disclaimed subject matter of the cruet that form no part of the claimed design.

1 Claim, 8 Drawing Sheets
